UNITED STATES PATENT OFFICE.

WILLIAM FULLER HOSFORD, OF OAK PARK, ILLINOIS, ASSIGNOR TO WESTERN ELECTRIC COMPANY, INCORPORATED, OF NEW YORK, N. Y., A CORPORATION OF NEW YORK.

WIRE-DRAWING MACHINE.

Application filed June 6, 1922. Serial No. 566,206.

This invention relates to improvements in wire drawing machines. One object of the invention is to provide a wire drawing machine with a driving mechanism so designed that there are a minimum number of operative connections between the said driving mechanism and the drawing elements of the machine, whereby power for driving the said drawing elements is conserved, the mechanism made capable of high speed operation, the machine rendered compact and a saving of floor space effected. To this end a machine made in accordance with this invention includes a driving mechanism and a clutch device mounted within the capstan or drawing element for operatively connecting and disconnecting said capstan to and from the driving mechanism.

Another object of the invention is to produce a wire drawing machine in which the wire drawing elements are enclosed within a compartment which is provided with doors so designed and mounted that they are adapted to completely close or completely open one side of the said compartment so that unobstructed access is provided to the drawing elements.

A further object of the invention is to produce a wire drawing machine so designed that the operation of stringing the machine with wire is facilitated. To this end the improved machine includes a series of sheaves all of the same diameter, which are each free to rotate on a common horizontal shaft which is mounted above and in substantially the same vertical plane with a second horizontal shaft upon which a conical capstan is supported, a series of dies being mounted between the sheaves and the capstan. The diameter of each sheave is less than the largest diameter of the capstan.

Other objects and advantages of the present invention will be set forth in the following description and particularly pointed out in the appended claims.

The accompanying drawings illustrate one embodiment of the invention, in which:

Fig. 1 is a side elevation, parts being broken away, of a machine embodying features of the invention;

Fig. 2 is an enlarged vertical sectional view of the capstan showing in detail the clutch mechanism for connecting it to and discon-

necting it from the driving elements of the machine;

Fig. 3 is an enlarged top plan view, partly in section, showing in detail the mechanism for mounting and operating the swinging doors, and

Fig. 4 is a fragmentary vertical sectional view taken on the line 4—4 of Fig. 3.

Referring now to the drawings in which like reference numerals designate similar parts throughout the several views, 10 represents a framework which supports a compartment 5 of substantially rectangular shape having top, bottom, back, and side walls 11, 12, 13, and 14 respectively. The front of the compartment may be closed by doors which will hereinafter be described in detail.

The wire drawing apparatus is mounted within the comparement 5 and comprises a horizontally disposed shaft 18 which is tubular in form and upon which is mounted a plurality of integral capstans 17—17 of different diameters. Supported above the shaft 18 are a plurality of sheaves 19 all of the same diameter and independently mounted upon a horizontally disposed shaft 20 suitably supported within the compartment 5. The sheaves preferably having the minimum diameter which it is possible to safely employ without introducing undue bending strains in the wire of the greatest diameter passing thereover. Mounted between the sheaves 19 and capstans 17—17 is a die block 21 carried by a bracket 22 secured to the back wall of the said compartment.

Heretofore wire drawing machines have been proposed employing a series of sheaves 90 of different diameters, each being free to rotate on a common horizontal shaft mounted above and in substantially the same vertical plane with a stepped cone shaped drawing capstan. Since in such a construction, it 95 was proposed to use sheaves of substantially the same diameters as the corresponding stepped portions of the capstan access to the die block would be somewhat obstructed, thus rendering the machine difficult to string 100 with wire. However, in a machine embodying the present invention, the sheaves being of the same diameter and such diameter being materially less than the diameter of the last or final stepped portion of the 105 capstan, the die blocks are rendered readily

accessible, thus materially facilitating the stringing of the machine with wire.

The shaft 18 is rotatably mounted within suitable anti-friction bearings 25 supported 5 by a bracket 26 carried by the rear wall 13 of the compartment 5. The other end of the shaft 18 is supported by an axial anti-friction bearing 27 supported by a sleeve 28 concentric with the shaft 18, the said sleeve being 10 rotatably mounted on an external anti-friction bearing 29 carried by a bracket 30 also secured to the rear wall 13 of the compartment 5. The sleeve 28 is also supported on an internal anti-friction bearing 31 mounted 15 between the said sleeve and the shaft 18. The shaft 18 and sleeve 28 are provided with thrust bearings 32 and 33 respectively. Secured to the outer end of the shaft 18 is a bevel pinion 40 which meshes with a bevel 20 gear 41 splined to a shaft 34 rotatably mounted within suitable bearings secured to the framework 10. The shaft 34 is driven by a motor or other suitable means (not shown).

25 The clutch mechanism for connecting the capstans 17-17 to and disconnecting them from the driving shaft 18 is shown in Figure 2 of the drawing, the clutch being illustrated in its operative position. This mechanism 30 comprises an annular member 70 secured to the inner end of the sleeve 18, the said member having secured thereto by means of a pin 71 a plurality of clutch disks 72. Alternately mounted between the clutch disks 72 are 35 clutch disks 73 which are secured by a pin 74 to the inner peripheral wall of a cup-shaped opening 75 made in the capstans 17-17. The disks 72 and 73 are movable longitudinally on the pins 71 and 74 respectively, and when pressure is exerted to force the disks together they form a driving connection between the capstans 17-17 and the sleeve 18, as readily understood. The means for forcing the disks 72 and 73 together comprises a plate 76 which engages the outermost disk, and when the plate is moved toward the right, into the position shown, serves to force the disks together sufficiently to cause them to rotate together. The plate 76 is fastened 45 to one end of a shaft 77 mounted within the sleeve 18. A transverse pin 79 is secured in the shaft 77 and projects through diametrically opposite longitudinal slots 80 in the sleeve 18 and into openings 80' formed in a sleeve 81' rotatable on axial bearings 82' carried by the housing 78.

50 The housing 78 is splined to the bracket 26 by a key 78' which prevents the housing from turning but permits it to slide longitudinally 60 of the sleeve 18. Through the medium of the pin 79 and slots 80 the shaft 77 and housing 78 are movable together longitudinally of the sleeve 18. Secured to the sides of the housing 78 at diametrically opposite points are 55 pins 81 which receive the bifurcated ends of

a fork member 82 which is pivoted at 83 to a link 84. The link has secured to its free end a pin 85 which fits within a slot formed in the upper end of a vertically reciprocable rod 86. The lower end of the rod 86 is connected by a link 91 with one end of a lever 92 which is pivoted at 93 to a bracket 94 carried by the framework 10. The other end of the lever 92 is connected by suitable mechanism 95 with a foot pedal 97.

When it is desired to revolve the capstans 17-17 the foot pedal 97 is depressed, which through the medium of the mechanism 95, lever 92 and link 91 causes the rod 86 to be moved downwardly, as viewed in Figs. 1 and 2. As the rod 86 moves downwardly the housing 78 is moved to the right, as viewed in Fig. 2, longitudinally of the shaft 18 through the medium of the pin 79, causing the plate 76 carried by the shaft to exert sufficient pressure on the disks 72 and 73 to cause them to form a driving connection between the sleeve 18 and capstans 17-17. The pedal may be released and the rod 86 locked in its downward position by means of a suitable mechanism 96 operatively connected with the mechanism 95. The mechanisms 95 and 96 are not illustrated or described in detail herein inasmuch as they are not essential to an understanding of the present invention and are fully disclosed in a co-pending application of J. N. Selvig, Serial No. 566,385, filed June 6, 1922.

When the mechanism 96 is released to unlock the rod 86 the said rod is restored to its initial position and the housing 78 and shaft 77 moved toward the left, as viewed in Fig. 2, by means of energy stored in a compression spring 87 which has one of its ends in engagement with the shaft 77 and its other end against a plug 99 screwed within the end of the sleeve 18. The housing 78 in moving toward the left, as above described, engages a brake member 89 carried thereby against the adjacent surface of an annular member 90 secured to the capstan and serves to stop the rotation thereof.

In wire drawing machines the former practice has been to connect the capstan by intermediate shafting with a clutch device mounted apart therefrom. By mounting the clutch within the capstan this intermediate shafting is dispensed with, resulting in a conservation of power and permitting higher speed operation. Furthermore, the capstan provides a housing for the clutch mechanism and since both the capstan and clutch mechanism only occupy the space necessary for the capstan alone, the over-all width of the machine is materially reduced and a saving of considerable floor space effected.

As previously stated, the front of the com-

partment 5 is closed by co-operating doors 100 and 101. The doors are each secured to one arm 102 of a bracket 103. These brackets are each provided with two other arms 104 and 105 spaced apart and integral therewith, as shown in Fig. 4. Mounted between arms 104 and 105 is the bifurcated end of a lever 106, portions 107 and 108 of the said lever carrying adjustable bearing pins 109 and 110 respectively which project within bearings 111 and 112 carried by the arms 104 and 105 respectively. The doors are supported on the levers 106 which are fastened to stub shafts 113 rotatably mounted within suitable bearings 114 carried by the top wall 11 of the compartment 5. One end of each of the shafts 113 has integral therewith a segmental gear 115, which gears mesh with each other. Each of the arms 104 is provided with a roller 116 which fits within an arcuate slot 117 formed in a plate member 118 secured to the top wall 11 of the compartment 5. The arcuate slots 117 are each provided with a curved portion 119 to receive the roller 116 when the doors are in their closed position, as shown in Fig. 3. Each of the doors 100 and 101 is provided with a suitable handle 120 for opening and closing them. When the doors are in their closed position, as shown in full lines in Fig. 3, they serve to completely close the front of the compartment 5 with the exception of a slot formed by cut-out portions 121 formed in the abutting edges of the door, the purpose of which will be hereinafter explained. To open the doors, either one is moved by means of its handle 120, the door being moved inwardly to the dotted line position shown in Fig. 3 by its hanger which is guided through the medium of the roller 116 and slot 117. The opening of either door causes a complementary movement of the other door through the medium of the segmental gears 115 which operatively connect the levers 106. Attention is called to the fact that when the doors are in their open position they are mounted at opposite sides of the capstans 17—17 and leave the front of the compartment entirely unobstructed.

A supply of wire to be reduced in diameter 50 is carried by a supply spool 50 suitably mounted at the front of the machine. The wire is guided from the supply spool over and under pulleys 51 and 52 respectively and then over the rear sheave 19 and through the first reducing die carried by the die block 21. The wire is then wound once around the capstan 17 of smallest diameter, after which it is passed upward and over the next sheave 19 and through the next reducing die carried by 55 the die block 21. The wire is then wound around the next capstan and then again over the next sheave 19 and through the next reducing die, etc., etc., until it is finally drawn down to the desired diameter by the last reducing die. From the final reducing die the

drawn wire passes around the capstan 17 of largest diameter and is guided by a pulley 57 rotatably mounted on a stationary arm 58 adjustably positioned on the shaft 20. From the pulley 57 the wire passes through the exit opening 121 in the closed doors 100 and 101 to a pulley 59 carried by an arm 60 and thence is led to a take-up spool 61 driven by suitable mechanism (not shown).

What is claimed is:

1. In a wire drawing machine, a horizontally disposed guide device, a tubular shaft disposed therebelow, a stepped drawing roll mounted thereon, a die block located intermediate said guide device and drawing roll, a die supported by said die block arranged

to have wire drawn vertically therethrough by said drawing roll, a friction mechanical clutch mechanism mounted within said stepped drawing roll for operatively connecting said drawing roll with the shaft, and means mounted within the shaft for controlling said clutch mechanism.

2. In a wire drawing machine, a horizontally disposed guide roll, a tubular shaft disposed therebelow, a stepped drawing roll mounted thereon, a die block located intermediate said guide and drawing rolls, a die supported by said die block arranged to have wire drawn vertically therethrough by said drawing roll, a friction mechanical clutch mechanism mounted within said stepped drawing roll for operatively connecting said drawing roll with the shaft, and a reciprocable member mounted within the shaft for controlling said clutch.

3. In a wire drawing machine, a horizontally disposed guide roll, a tubular shaft disposed therebelow, a stepped drawing roll mounted thereon, a die block located intermediate said guide and drawing rolls, a die supported by said die block arranged to have wire drawn vertically therethrough by said drawing roll, a friction mechanical clutch mechanism mounted within said stepped drawing roll for operatively connecting said drawing roll with said shaft, a reciprocable member mounted within said shaft for operating said clutch mechanism, and means for controlling said clutch.

4. In a wire drawing machine, a horizontal shaft, a plurality of sheaves independently mounted thereon, a horizontal driving shaft mounted below said first mentioned shaft, a capstan mounted on said driving shaft, a plurality of dies mounted between said sheaves and capstan, a friction mechanical clutch mounted within said capstan for operatively connecting the capstan with the driving shaft, a reciprocable member operatively associated with said clutch mechanism, and means for reciprocating said member to operate the clutch.

5. In a wire drawing machine, a compartment having a top, bottom, rear and side

walls, wire drawing mechanism located within said compartment, a pair of doors for closing the front of said compartment, the adjacent edges of said doors being provided with 5 cut-out portions so that when the doors are closed an exit opening for the drawn wire is provided, a take-up mechanism located outside of said compartment, and a guide device also located outside of said compartment and 10 associated with said take-up mechanism for directing and supporting the wire from the opening in said doors to the take-up mechanism.

6. In a wire drawing machine, a compartment having top, bottom, rear and side walls, wire drawing mechanism located within said compartment, a pair of doors for closing the front of said compartment, the adjacent edges of said doors being provided with cut-out 15 portions so that when the doors are closed an exit opening for the drawn wire is provided, a take-up mechanism located outside of said compartment, a guide device also located outside of said compartment, supporting 20 the wire between said wire drawing mechanism and said take-up mechanism as passed through said opening, and an arm supporting said guide device and functioning to maintain the tension of the wire substantially 25 uniform, said wire oscillating in the opening 30 in said doors in accordance with the movement of said arm.

7. In a wire drawing machine, a compartment having top, bottom, rear and side walls, wire drawing mechanism located within said compartment, a pair of doors for closing the front of said compartment, the adjacent edges of said doors being provided with cut-out 35 portions so that when the doors are closed 40 an exit opening for the drawn wire is provided, means for permitting the movement of the doors to give an unobstructed access to the wire drawing mechanism, a take-up mech-

anism located outside of said compartment, and a guide device also located outside of said 45 compartment and associated with said take-up mechanism for directing and supporting the wire from the opening in the doors to said take-up mechanism.

8. In a wire drawing machine, a compartment having top, bottom, rear and side walls, wire drawing mechanism located within said compartment, a pair of doors for closing the front of said compartment, the adjacent edges of said doors being provided with cut-out 50 portions so that when the doors are closed an exit opening for the drawn wire is provided, an idler pulley located within said compartment over which the drawn wire passes to the opening in said doors, a take-up 55 mechanism located outside said compartment, and a guide device also positioned outside of said compartment and located intermediate the take-up mechanism and said pulley for receiving said wire as it passes 60 from the opening in said doors and directing 65 it to said take-up mechanism.

9. In a wire drawing machine, a compartment having a top, bottom, rear and side walls, wire drawing mechanism located within said compartment, a pair of doors for closing the front of said compartment having an opening to allow the exit of the wire and positioned to allow the entrance of the wire 70 underneath one of the doors, take-up and supply mechanisms located outside of said compartment and below said doors, and guide devices also located outside of said compartment for guiding the wire to said drawing mechanism from the supply mechanism and 75 receiving said wire from the opening between said doors to guide the wire to said take-up mechanism.

In witness whereof, I hereunto subscribe my name this 31st day of May, A. D. 1922.

WILLIAM FULLER HOSFORD
